UNITED STATES PATENT OFFICE.

JOSEPH EYSSÉRIC, OF CARPENTRAS, FRANCE.

WIND-SHIELD.

No. 802,082.

Specification of Letters Patent.

Patented Oct. 17, 1905.

Application filed May 27, 1905. Serial No. 262,642.

To all whom it may concern:

Be it known that I, JOSEPH EYSSÉRIC, a citizen of the French Republic, residing at Carpentras, in the Department of la Vaucluse, France, have invented new and useful Improvements in Wind-Shields, of which the following is a specification.

This invention relates to a wind-shield which is applicable to any kind of vehicle or to a boat or ship.

The object of the invention is to divert the horizontal current of air due to the speed of the vehicle or the like or to a head-wind and to divert it to pass above the head of the driver or observer.

An improved wind-shield which is given as an example and is constructed according to this invention is illustrated in the following drawings, in which—

20 Figure 1 shows it in side view as attached to a motor-car. Fig. 2 shows the same device in front elevation. Fig. 3 illustrates in more detailed side view an adjustable supplementary part employed to increase the area of the shielding-surface.

The improved shield, which is essentially an apron, is fixed to the lower part of the car by an adjustable bracket, (shown at *a*.)

The main part of the shield consists of two 30 curved portions, viz: first, one, *b c*, whose chord forms an angle of about forty-five degrees with the horizontal; second, an upper second part *c d*, struck to a smaller radius, (about from fifteen to twenty centimeters.)

35 This second part is angularly adjustable, so that it is possible to vary the angle of a tangent struck from its upper edge, as is hereinafter shown. Further, an additional adjustable part permits the surface of the upper portion 40 of the shield to have its area varied. This adjustable part (indicated at *d e*) is concentric with the part *c d* and may be slid thereon to effect the necessary variation of area of surface of the upper part of the shield. The 45 angle of the tangent referred to and as shown in Fig. 1 is about at ninety degrees with the horizontal.

The portion *b c* of the shield may be cut out or notched to allow the entrance of part of 50 the steering-wheel, the opening so formed being covered with a hood *f*.

With the apparatus constructed as described and in use and with the upper portion disposed with its tangent as indicated at *d* in 55 the proper direction there is produced behind the upper part of the shield a region of calm

air the vertical section of which approximately follows a parabolic curve; but in its application to motor-cars particularly the height of this calm region would not always 60 be sufficient, for it is of the greatest importance that the driver should be able to see well in front of his car and at the same time be protected. It has therefore been necessary to extend the shielded region. The desired result has been attained by the addition of a further part *h g* to the lower part *b c* of the shield, but of smaller depth than this lower part and fixed parallel to the main surface at a distance of about ten centimeters. 70 The parallelism of these two parts is essential to efficiency.

The part *c d* must have its inclination varied more or less according to the conditions under which it is working. It has therefore 75 been made movable around the hinge *i*. (See Fig. 3, in which figure the upper part is shown in greater detail.)

When the part shown at *d*, Fig. 1, occupies the position indicated at *d'* in Fig. 3, the 80 tangent before referred to will be at an angle of about forty-five degrees with the horizontal, and this position is convenient for use with slow speeds. With the same part in the position indicated at *d*, Fig. 3, the tangent is 85 at about sixty degrees with the horizontal. This position is suitable for average speeds of from fifty to fifty-five kilometers an hour. When the part *d* is moved back to the position *d''* in Fig. 3, the shield is in the position 90 for use with high speeds.

As before explained, to the part *c d* may be added a second concentric surface, which lies upon the surface *c d* and may be movable thereon to increase or diminish at will the 95 height of this part. This second surface is indicated by the broken lines in Fig. 3, and it may be secured in place by winged nuts or equivalents. There are two ways of varying the angle of the tangent to the upper edge 100 of *c d*, either by angularly moving the part indicated in the full lines to the positions *d* *d''* or by extending or moving the second concentric surface, as shown in the dotted lines. The angle of the tangent to the horizontal (*j j'*) is thus variable from forty-five degrees to ninety degrees.

In the arc at *k k' k''* are indicated the centers of the curve of the part *c d* in its various positions.

For the better understanding of the drawings the extra sliding piece and its thumb-

screws to regulate its position have only been shown in the position marked *d*.

Having now particularly described and ascertained the nature of my invention and in what manner the same is to be performed, I declare that what I claim as my invention, and what I desire to secure by Letters Patent, is—

A wind-shield for a vehicle, boat, or the like, consisting of curved upper and lower parts hinged together and having their concavities presented to the front, a regulatable sliding part secured to the upper part of the

shield, and a supplementary curved plate attached to the main lower part of the shield and parallel therewith, all substantially as 15 hereinbefore described.

In testimony whereof I have signed my name to this specification in the presence of two subscribing witnesses.

JOSEPH EYSSÉRIC.
